(57) **CLAIM**

The ornamental design for a bottle, as shown and described.

DESCRIPTION

FIG. 1 is a perspective view of a bottle according to a first embodiment of my new design;

FIG. 2 is front view thereof;

FIG. 3 is a rear view thereof;

FIG. 4 is a left side view thereof;

FIG. 5 is a right side view thereof;

FIG. 6 is a top view thereof;

FIG. 7 is bottom view thereof;

FIG. 8 is an enlarged fragmented view thereof, taken from FIG. 2;

FIG. 9 is a perspective view of a bottle according to a second embodiment of my new design;

FIG. 10 is front view thereof;

FIG. 11 is a rear view thereof;

FIG. 12 is a left side view thereof;

FIG. 13 is a right side view thereof;

FIG. 14 is a top view thereof;

FIG. 15 is bottom view thereof; and,

FIG. 16 is an enlarged fragmented view taken from FIG. 10. The broken lines in the drawings illustrate the portions of the bottle that form no part of the claimed design.
